of California

Application June 9, 1950, Serial No. 10,442

Term of patent 7 years

(Cl. D14—6)

To all whom it may concern:

Be it known that we, Earl F. Gates and Otto Elsebusch, citizens of the United States of America, residing in the cities of Long Beach and Los Angeles, respectively, in the county of Los Angeles, State of California, have invented a new, original, and ornamental Design for a Wind Deflector or Similar Article, of which the following is a specification, reference being had to the accompanying drawing, forming a part thereof.

Fig. 1 is a side elevational view of the wind deflector showing our new design;

Fig. 2 is a front elevational view thereof;

Fig. 3 is a bottom view of the same; and

Fig. 4 is a cross-sectional view taken on the line 4—4 of Fig. 1, showing the forward lip and the shape of the attaching flange.

We claim:

The ornamental design for a wind deflector or similar article, substantially as shown.

EARL F. GATES.
OTTO ELSEBUSCH.
